(57) CLAIM

The ornamental design for an airbrush make-up cabinet, as shown and described.

DESCRIPTION

FIG. 1 is a perspective view of my design;

FIG. 2 is a front view of the design of FIG. 1;

FIG. 3 is a rear view of the design of FIG. 1;

FIG. 4 is a side view of the design of FIG. 1;

FIG. 5 is a second side view of the design of FIG. 1;

FIG. 6 is a top view of the design of FIG. 1; and,

FIG. 7 is a rear perspective view of the design of FIG. 1.

The broken line showing of the legs in FIGS. 2-5 is for the purpose of illustrating one possible form of such legs and forms no part of the claimed design.
